UNITED STATES PATENT OFFICE.

JOHN NIELSON, OF BANDON, OREGON.

LANTERN.

1,112,227.

Specification of Letters Patent. Patented Sept. 29, 1914.

Application filed May 28, 1914. Serial No. 841,526.

To all whom it may concern:

Be it known that I, JOHN NIELSON, a citizen of the United States, and a resident of Bandon, in the county of Coos and State of Oregon, have made certain new and useful Improvements in Lanterns, of which the following is a specification.

My invention is an improvement in lanterns, and has for its object to provide a device of the character specified, wherein the chimney is mounted for guided movement toward and from the burner, and is normally spring pressed upward, away from the burner, to facilitate lighting the lantern, and wherein releasable latch mechanism is provided for normally holding the globe in proper position with respect to the burner.

In the drawings: Figure 1 is a side view of a lantern constructed in accordance with the improvement, with parts in section, Figs. 2, 3 and 5 are sections on the lines 2—2 and 3—3, and 5—5, respectively, of Fig. 1, Fig. 2 looking in the direction of the arrows, and Fig. 4 is a view similar to Fig. 2 showing the parts in another position.

In the present embodiment of the invention, the body 1 of the lantern is of any usual or desired construction, and is provided with a burner 2, which may also be of any usual or desired construction, and the chimney 3 is mounted above the burner in the usual manner.

A substantially rectangular frame consisting of side members and end members 5 and 6 is connected with the body by means of the end member 6, the said member being sectional, and the sections being held in bearing sleeves 7 on the body. The sleeves 7 are in alignment, and are at opposite sides 40 of the burner.

A ring 8 of wire or the like is connected with the frame 4—5—6, and the said ring encircles the chimney, forming a part of the frame for connecting the chimney with the burner. A shield or cap 9 of metal or the like and of concavo-convex form is arranged above the upper end of the chimney in spaced relation, the said shield having a central threaded nipple 10, through which is 50 threaded the lower end of a rod 11.

A ring 12 encircles the reduced upper end of the chimney, the said ring resting normally upon an annular shoulder or rib 13 formed in the chimney, and at one end the 55 ring is provided with an extension 14 con-

nected with the shield 9, and at the other with an extension 15 which extends through an opening in the shield, and is provided with a finger piece 15^a for convenience in operating the ring. The extension 14 of the 60 ring is resilient, and normally holds the ring in engagement with the rib 13. The upper end of the chimney may be released from the ring by lifting upward on the finger piece 16 to permit the chimney to be removed for cleaning or the like.

The ring and the extensions 14 and 15 and the finger piece 16 are formed from wire bent to shape, and the edge of the shield 9 is reinforced, as shown at 17 in the usual 70 manner. Arms 18 extend downwardly from the reinforcing ring or bead 17 of the shield, to a connection with the ring 8 before mentioned. The upper ends of the arms or rods 18 are soldered or brazed to the reinforcing 75 ring 17, and the said arms or rods are then bent around the ring 8, as shown at 19. Both arms extend to the level of the lower end of the chimney, and one of the arms is then bent inward, as shown at 20 to a 80 connection with a ring 21 which encircles the lower end of the chimney.

The ring 21 is provided with an extension 22 in alignment with the portion 20 before mentioned, and the extension is connected 85 with the lower end of the other arm 18. The arrangement is such that when the shield 9 is lifted in a manner to be presently described, the supporting frame for the chimney consisting of the rings 8 and 21, and the 90 arms 18, and the extensions 20 and 22 will also be lifted with respect to the frame 4—5—6. From an inspection of Fig. 5, it will be noted that the side members 4 of the frame engage grooves 23 formed in the 95 ring 8 by bending a portion of the said ring inward. The ring 8 thus has a sliding connection with the said side members of the frame.

A bail 24 is connected with the upper 100 member 5 of the frame for convenience in carrying the lantern, and a telescoping casing is arranged between the rod 11 before mentioned and the upper cross member 5 of the frame 4—5—6. The upper end of the 105 rod 11 is threaded and is engaged by a nut 25, and the inner section 26 of the sectional casing is engaged with the nut.

The nut is provided with a central opening for receiving the upper end of the rod, 110

and the exterior of the nut is threaded for engagement by the upper end of the inner section of the casing. The nut is provided with an annular flange 27, and the outer section 28 of the sectional casing is cup shaped, as shown, the lower end thereof being secured to the cross member 5 of the frame 4-5-6. The inner section 26 of the sectional casing slips in the outer section, and 10 a coil spring 29 is arranged in the sectional casing between the closed lower end of the outer section and the lower end of the nut 25, the said spring acting normally to force the rod upward, and as a consequence to force the chimney upward away from the burner. 15

A latch lever 30 is pivoted to the outer section, as indicated at 31, and the said lever is provided at its upper end with an 20 angular lug 32 which extends through an opening 33 in the outer section of the casing into engagement with an opening 34 in the inner section when the said opening 34 is in register with the opening 33. A coil 25 spring 35 engages the lower end of the lever and normally acts to force the lug 32 toward the rod 11.

It will be noted that the shield is reinforced, as indicated at 36, at the nipple 10, 30 the reinforcing plate or washer being on the inner face of the shield. The inner section 26 of the casing is provided with a longitudinally extending slot 37, with which engages the inner end of a pin 38 connected 35 to the outer section, for constraining the sections from angular movement with respect to each other, and for guiding them in the movement to be later described.

The operation of the improved lantern 40 is as follows: Normally, that is when the burner is ignited, the parts will occupy the position shown in Fig. 1. When it is desired to extinguish the lantern or to light the same, the lower end of the latch lever 45 30 is depressed, to release the lug 32 from the opening 34 of the inner section of the casing. As soon as the said inner section is released, the spring 29 forces the inner section of the casing, the rod 11, the shield 50 9, and the chimney upward away from the burner, thus permitting access to the wick for extinguishing or lighting the same. After the wick has been extinguished the parts may be left in this position if desired, 55 or the chimney may be returned to original position. After igniting the wick, the hand of the user is engaged with the head 27 of the nut 25, and the said head is pushed downward with respect to the body 1 of the lantern, when the lug 32 engages the opening 34 of the inner casing, and locks 60 the parts in the position of Fig. 1. The chimney may be removed from its supporting frame when it is lifted, by pressing the 65 finger piece 16 upward, to release the ring

12 from the top of the chimney, and the chimney may be lifted out in the usual manner.

It will be evident that many changes might be made in the construction without departing from the spirit of the invention as specified by the appended claims.

The invention consists in its simplest form, in an arrangement comprising a body having a guide frame, a chimney having a supporting frame slidably connected with the guide frame for movement toward and from the body, together with a spring arranged between the frames and normally acting to move the chimney or supporting frame away from the body, and the latch mechanism normally holding the parts in adjusted position, and releasable to permit the spring to act.

I claim:

1. A lantern comprising a body, a substantially rectangular frame connected with the body and extending upwardly therefrom, a chimney supporting frame slidable on the first-named frame, a chimney releasably connected with the chimney supporting frame, a shield in connection with the chimney supporting frame, a rod extending upwardly from the shield, a sectional casing arranged above the first-named frame and comprising a section connected with the said first-named frame, and a section connected with the outer end of the rod, the sections being slidably connected, a spring within the casing and normally acting to move the sections away from each other and to lift the chimney supporting frame away from the body, a latch for holding the sections with the chimney supporting frame in lowered position, said latch being releasable, and a spring normally holding the latch in engaging position.

2. A lantern comprising a body, a substantially rectangular frame connected with the body and extending upwardly therefrom, a chimney supporting frame slidable on the first-named frame, a chimney releasably connected with the chimney supporting frame, a shield in connection with the chimney supporting frame, a rod extending upwardly from the shield, a sectional casing arranged above the first-named frame and comprising a section connected with the said first-named frame, and a section connected with the outer end of the rod, the sections being slidably connected, a spring within the casing and normally acting to move the sections away from each other and to lift the chimney supporting frame away from the body.

3. A lantern comprising a body, a substantially rectangular frame connected with the body and extending upwardly therefrom, a chimney supporting frame slidable on the first-named frame, a chimney releas-

ably connected with the chimney supporting frame, a shield in connection with the chimney supporting frame, a rod extending upwardly from the shield, a sectional casing arranged above the first-named frame and comprising a section connected with the said first-named frame, and a section connected with the outer end of the rod, the sections being slidably connected, a spring 10 within the casing and normally acting to

move the sections away from each other and to lift the chimney supporting frame away from the body, and releasable means for normally holding the chimney supporting frame in lowered position.

JOHN NIELSON.
